Primary Examiner — Susan Bennett Hattan*Assistant Examiner* — Landon Thomas Cassell(74) Attorney, Agent, or Firm — Patterson Intellectual Property Law, P.C.; Jerry Turner Sewell(57) CLAIM

The ornamental design for a “applicator head for percussive massage device,” as shown and described.

DESCRIPTION

FIG. 1 is an upper front perspective view of an applicator head for percussive massage device of our new design;

FIG. 2 is a top view thereof;

FIG. 3 is a right side view thereof;

FIG. 4 is a front view thereof;

FIG. 5 is a rear view thereof;

FIG. 6 is a left side view thereof; and,

FIG. 7 is a bottom view thereof.

The broken lines in the drawings are for the purposes of illustrating portions of the applicator head for percussive massage device, which form no part of the claimed design.

1 Claim, 3 Drawing Sheets(56)
